MULTIPLE-UNIT TRAIN

Andrew H. Candee, Pittsburgh, Pa., assignor to Westinghouse Electric & Manufacturing Company, East Pittsburgh, Pa., a corporation of Pennsylvania

Application May 15, 1941, Serial No. 393,519

4. Claims. (Cl. 105—4)

My invention relates, generally, to multiple-unit trains and, more particularly, to self-propelled rail cars suitable for multiple-unit operation.

The operation of trains for suburban and interurban service usually involves the use of passenger cars hauled by a locomotive. In some cases such passenger cars have been provided with electrical equipment for independent operation or for assembly into trains of the required length, these cars then being operated in multiple, without a locomotive, by a single operator.

In a great many cases, the use of locomotives for hauling passenger trains imposes economic handicaps upon a railroad, yet to electrify the road to permit the operation of multiple-unit trains is not always economically feasible. Consequently, a great many Diesel-powered and gasoline-powered rail cars are in operation in this country and Canada and some of these are built for multiple operation. However, trains of this type, as built in the past have certain objectionable features, some of which are:

The mounting of an engine on a passenger car body subjects that body and the passengers to continuous vibration, sometimes very annoying to passengers;

Repairing or overhauling the engine requires removing the entire car from service, thereby losing revenue;

It is difficult to insulate the passenger compartment against engine noise;

With an operator's compartment in the engine room, passage through the engine room to the next car is difficult for passengers;

The ratio of revenue space to engine-room space is small.

Accordingly, an object of my invention is to overcome the foregoing objections to self-propelled rail cars.

A more general object of my invention is to provide a self-propelled rail car which shall be simple and efficient in operation and which may be economically manufactured and installed.

Another object of my invention is to provide a self-propelled rail car suitable for multiple-unit operation.

Other objects of my invention will be explained fully hereinafter or will be apparent to those skilled in the art.

In accordance with my invention, each unit of a self-propelled multiple-unit train comprises three or more separate body sections, articulated and carried on three or more trucks. In one arrangement, the first section is utilized for revenue purposes, with motors on the supporting trucks and a control station located at the front end. The opposite end of this revenue section is articulated with the second section on a single

truck. The third section is, in most cases, a duplicate of the first section in a reverse position. The second or middle section carries all of the power plant equipment, which is so arranged that free and safe passage is allowed between the first and third sections. In a modified arrangement only three trucks are utilized and the first and third body sections are articulated on the center truck. The second body section is mounted over the articulating center pin and partly supported on the other two sections.

For a fuller understanding of the nature and objects of my invention, reference may be had to the following detailed description, taken in conjunction with the accompanying drawings, in which:

Figure 1 is a plan view partly in section, of a rail car embodying my invention;

Fig. 2 is a view, in side elevation, of the rail car shown in Fig. 1;

Fig. 3 is a reduced view, in side elevation, of a multiple-unit train composed of rail cars of the type shown in Figs. 1 and 2; and

Figs. 4, 5 and 6 are views similar to Figs. 1, 2 and 3, respectively, of a modified form of the invention.

Referring to the drawings, and particularly to Figs. 1, 2 and 3, each unit of a multiple-unit train comprises three sections, A, B and C, which are articulated and carried on four trucks 1, 2, 3 and 4. As shown, the sections are articulated over the trucks 2 and 3. Thus, the truck 2 jointly supports the sections A and B, and the truck 3 jointly supports the sections B and C. The truck 1 supports the front end of the section A and the truck 4 supports the rear end of the section C.

The section A may be utilized for revenue purposes and is provided with a passenger compartment 5 and a control compartment 6 located at the front end of the car. Likewise, the section C may be utilized for revenue purposes, and is provided with a passenger compartment 7 and a control compartment 8. The section C is a duplicate of the section A reversed in position. A controller 9 is provided in each one of the control compartments for controlling the operation of the car. It will be understood that only the controller which is located at the head of the car will be utilized; and, that when two or more cars are being operated in multiple, the complete train will be controlled from the control compartment at the head end of the train.

All of the power plant equipment, such as an engine and generator 10 and a control panel 11, is located in the intermediate section B. As shown, the power plant equipment is enclosed by a partition 12, thereby providing a passageway 13 through which passengers may pass from one

of the end sections to the other without coming in contact with the power plant equipment.

In order to propel the car, motors 14 are provided on the trucks 1 to 4. The motors may be mounted in the trucks in the usual manner. The power for operating the motors is supplied from the engine-generator unit 10 and is conducted to the motors through cables 15. Additional cables 16 are provided for connecting the controllers 9 in order that the motors may be controlled in the usual manner. Jumper cables 17 are provided for interconnecting the cars when operated in multiple.

In order that it will not be necessary to remove the entire car from service when it is desired to repair or overhaul the power plant equipment, the intermediate section B is so constructed that the entire body section and the power plant equipment may be removed from the car by lifting the body B from articulating center pins 18 and 19 on the trucks 2 and 3, respectively. Thus, a spare power plant section may be placed in the car and the car kept in service while the repair work is being done on the power plant equipment. It will be understood that one spare unit which is interchangeable with the power plant units on a number of cars will normally enable all of the cars to be kept in revenue service at all times. In this manner the income derived from a predetermined number of cars may be materially increased without greatly increasing the initial cost.

In the modification of the invention shown in Figs. 4, 5 and 6, the three body sections A, B and C are similar to those hereinbefore described. Thus, the sections A and C are utilized for revenue purposes and the section B contains the power plant equipment, as previously explained. However, only three trucks 21, 22 and 23 are provided and the bodies A and C are articulated on the center truck 22. The body B is removably placed over the articulating center pin 24 and is jointly supported by the bodies A and C. Centering springs 25 are provided for retaining the body B in alignment with the bodies A and C while the car is operating on straight track. Guiding pins 26 and cooperating slots 27 are provided to permit the articulated unit to pass around curves.

As explained hereinbefore, the entire body section B, including the power plant equipment, may be readily removed from the car, and a spare unit placed in service, while the equipment is being repaired, thereby avoiding removing the entire car from service. The car is propelled by motors 28 provided on the end trucks 21 and 23, no motor being provided on the center truck 22. Control compartments 6 and 8, similar to those previously described, are provided at the ends of the car. The usual controllers 9 are provided for controlling the operation of the motors.

From the foregoing description, it is apparent that I have provided an articulated rail car of the Diesel or other self-propelled type which is particularly suitable for multiple-unit operation, and which has numerous advantages over cars of previously known types. Thus, by locating all of the power plant equipment in a removable body section which is entirely independent of the revenue body sections, the power plant body may be readily removed in case it is necessary

to repair the equipment. Furthermore, the revenue sections are not subjected to noise and vibration from the power plant equipment. Also, a convenient passageway is provided which enables passengers to pass between the passenger compartments.

I do not desire to be restricted to the particular form or arrangement of parts herein shown and described, since it is evident that they may be changed and modified without departing from the spirit and scope of my invention as defined in the appended claims.

I claim as my invention:

1. An articulated rail car comprising, revenue body sections disposed at the ends thereof, a power generating body section disposed between the revenue sections, an articulated frame for supporting the body sections, a power generating unit disposed in the power generating body section, said power generating body section and said power generating unit being jointly removable from the frame, and a longitudinal partition in the power generating body section to provide a free passageway between the revenue body sections.

2. An articulated rail car comprising, revenue body sections disposed at the ends thereof, a power generating body section disposed between the revenue sections, an articulated frame for supporting the body sections, a power generating unit disposed in the power generating body section, said power generating body section and said power generating unit being jointly removable from the frame, a supporting truck disposed at each end of the car, propelling motors in said trucks, additional trucks for jointly supporting said articulated frame, and a longitudinal partition in the power generating body section to provide a free passageway between the revenue body sections.

3. An articulated rail car comprising, revenue body sections disposed at the ends thereof, a power generating body section disposed between the revenue sections, an articulated frame for supporting the body sections, a power generating unit disposed in the power generating body section, said power generating body section and said power generating unit being jointly removable from the frame, a supporting truck disposed at each end of the car, additional trucks for jointly supporting said articulated frame, propelling motors in said trucks, a control station disposed in each revenue section, and a longitudinal partition in the power generating body section to provide a free passageway between the revenue body sections.

4. An articulated rail car comprising, end sections with an intermediate section disposed between said end sections, a power generating unit disposed in the intermediate section, an articulated frame for supporting said sections, said intermediate section and said power generating unit being jointly removable from the frame, a truck disposed between each end section and the intermediate section for jointly supporting said sections, an additional truck under each end section for independently supporting the end section, propelling motors in the independent trucks, and a longitudinal partition in the intermediate section to provide a free passageway between the end sections.

ANDREW H. CANDEE.
